R. McNamee

Attorney

UNITED STATES PATENT OFFICE

THEODORE BOSSARD, OF SALT LAKE CITY, UTAH, ASSIGNOR TO RESEARCH ENGINEERING LABORATORIES, INC., A CORPORATION OF UTAH

FUELING SYSTEM

Application filed August 14, 1929. Serial No. 385,715.

My invention relates to fueling systems and has for its object to provide a means for raising the fuel from the tank from which it may be drawn to the carburetor.

5 A further object is to provide a booster for use in drawing the fuel from the tank, which booster will increase the suction of either the carburetor, the pump, or the vacuum tank, aiding in drawing the fuel from the tank.

These objects I accomplish with the device illustrated in the accompanying drawings in which similar numerals and letters of reference indicate like parts throughout the several 15 views described in the specification forming a part of this application and pointed out in the appended claim.

In the drawings in which I have shown the best and most preferred manner of building 20 my invention Figure 1 is a section of a portion of the tank showing my device therein sectioned to show the operating portions thereof. Figure 2 is a plan view of the booster with the lead pipe removed therefrom and 25 the booster removed from the tank.

In the drawings I have shown the tank as A and through the bottom of which I bore and thread a hole 1. Into the hole 1, I place a screen carrying casting 2, having the lower 30 end threaded to screw into the said hole and having a cap 3 screwed on the lower end thereof forming a chamber 4 in the end thereof. Screen holding flanges 5 are formed on the outer periphery of the casting 2, spaced 35 from each other, with one near the top end and the other making the flange on which the casting rests when it is screwed down into the hole 1. A screen 6 is then secured around the casting 2 having the top and bottom ends secured to the flanges 5. In the top end 40 of the said casting 2, I place an upright air pipe 7 which pipe has its top end secured in a cylindrical socket 8. The socket 8 is secured through a threaded hole in the top side of the tank A and an elbow 9 is screwed onto the top free end of the socket 8. An air pipe 10 is screwed into the end of the elbow 9 and said pipe leads to any desired source of air supply preferably to an air filter or cleaner 45 which may be pre-heated by the heat of the

exhaust of an engine. The booster 11 is then placed down into the casting 2, and having outward radially extending bosses 18, 19, and 20 which hold the booster space equally from the walls of the casting 2 and a port 16 is provided through the boss 18 and a port 17 is formed through the casting 2 to provide means of allowing the fuel to pass from within the screen 6 into the booster. The booster is formed with a tapered hole 12 in and extending down from the top end thereof and a bore 13 is formed in the bottom end of the booster into which bore the end of the bore 12 terminates, with the body of the casting 2 which surrounds the extreme end of the bore, formed in a frusto-conical portion 15a, which portion, extends down into the bore 13. A plug 14 is then pressed into the end of the bore 13 and the top end of the plug is also formed frusto-conical similar to the end portion of the bore 12. A bore 14a is formed in the plug 14 having the lower end curved outwardly and having the upper portion thereof with the walls parallel. The plug 14 is so placed in the bore 13 as to leave an annular 55 space 15 between the upper end of the plug and the end of the casting within the bore, and the port 16 is in direct communication and bored into the space 15. A pipe 21 is secured in the top end of the booster 11 and 60 an elbow 22 and pipe 23 connect the booster and pipe 21 with the carburetion vacuum tank or pump as used.

The operation of my device is as follows: 65 Air is sucked through the pipe 23, the elbow 22 and the pipe 21 by the carburetor, the vacuum tank, or the pump, or other fueling system and as this air is drawn therethrough it is drawn up through the tapered bore 12, and the bore 14a of the plug 14, and air is drawn 70 through the casting 2, the pipe 7 and the pipe 10, and the fuel is drawn through the ports 16 and 17 into the annular space 15 where it is mixed with the air and drawn up through the pipe 21 in the form of a vapor. Should 75 the engine be stopped the fuel will enter through the ports 17 and 16 into the space 15 and down through the bore 14a into the chamber 4 up around the walls of the booster within the casting 2 and into the pipe 7 to 80

seek the level of the fuel in the tank, and for starting the motor the suction through the pipe 21 will draw raw fuel in the unmixed stage through the said pipe until such time as 5 all fuel is drawn from the pipe 7, the casting 2, the chamber 4 and the opening 15 and at such time the suction therein will then draw air through the same source to the opening 15 where it will then be mixed with the raw 10 fuel to form the vapor. This aids the starting of the motor giving a raw fuel instead of a vapor through the pipe 23.

Having thus described my invention I desire to secure by Letters Patent and claim:

15 A booster for use with fuel systems consisting of a screen casting secured in the bottom of a tank; a screen around said casting; a port connecting the exterior of said casting with a booster member carried therein; a 20 tapered hole through said booster; a bore in the bottom end of said booster; a plug in said hole having a bore therethrough, said plug being spaced from the end of the tapered hole; a port connecting said space with the 25 port through the casting; a pipe to allow air to be drawn down into said casting and up through said booster; and a pipe connecting the top end of the tapered hole in said booster with means of carburetting the fuel.

30 In testimony whereof he has affixed his signature.

THEODORE BOSSARD.
